UNITED STATES PATENT OFFICE.

EDWARD W. BREYLEY AND JAMES U. DUFFY, OF CLEVELAND, OHIO.

CAR-STOP.

1,276,023.

Specification of Letters Patent. Patented Aug. 20, 1918.

Application filed November 22, 1917. Serial No. 203,831.

To all whom it may concern:

Be it known that we, EDWARD W. BREYLEY and JAMES U. DUFFY, citizens of the United States, and residents of Cleveland, county of Cuyahoga, and State of Ohio, have jointly invented a new and useful Improvement in Car-Stops, of which the following is a specification, the principle of the invention being herein explained and the best 10 mode in which we have contemplated applying that principle, so as to distinguish it from other inventions.

The present device relates to a stop for cars which may be either permanently secured adjacent the end of a section of track to act as a bumper, or which may be placed in any desired location along a track to stop cars temporarily. Use is made of a slideable shoe which is adapted to receive the car 15 wheel and move along therewith, and which is also adapted to retard the movement of the car and finally stop the same when it strikes a permanent stop block attached to the rail. Other means are provided for returning the shoe to its original position when the car is withdrawn and for releasing the shoe at the desired distance ahead of the permanent stop.

The annexed drawings and the following 20 description set forth in detail certain mechanism embodying the invention, such disclosed means constituting, however, but one of various mechanical forms in which the principle of the invention may be used.

35 In said annexed drawings:—

Figure 1 is a side elevation of our stop showing the car wheel during return movement; Fig. 2 is a side elevation showing the car wheel in its stopped position; Fig. 3 is a 40 plan view showing the device in position to receive a car wheel; Fig. 4 is a side elevation showing a modified form of return mechanism; Fig. 5 is a side elevation of a modified form of bumper; Fig. 6 is a plan view of a 45 form of cam shown in Fig. 4; Fig. 7 is a section taken on the line 7—7, Fig. 2; Fig. 8 is a section taken on the line 8—8, Fig. 3; Figs. 9 and 10 are sectional views taken on the lines 9—9 and 10—10 of Fig. 5; Fig. 11 50 is a detail view of the return mechanism shown in Fig. 4.

The mechanism is adapted to be placed on the rail 1, it being understood that the devices are generally used in pairs, although 55 only one device and rail are illustrated in

the drawings. The mechanism consists of a permanent stop block 2 which will be securely attached to the rail by means of bolts 3, either near the end of the rail, or at a point along the same where the car is to be stopped. This block is recessed along the inner edge of the rail to allow a car wheel to pass over it so that it may be left in place permanently.

A slideable skid or shoe 4 is also mounted 60 on the rail, and the shoe is adapted to receive a car wheel thereupon, the forward face being of the same shape as the rail but being curved to fit the car wheel, as shown in Fig. 2. This shoe, or slideable skid 4, is hollow in the center, and has a brace 5 as shown. The skid rests on the ball of the rail and has depending legs 6 which surround the ball of the rail and engage under the same as shown in Fig. 7. The shoes or skids are adapted 70 to be slid on to the rails from the end, but where the device is to be used along a track instead of at the end the shoes will be formed as shown in Fig. 5.

In this modified form, the forward legs 11 80 extend down past the rail, but do not engage beneath the ball. The rear leg 12 is formed integrally with the skid and extends past and under the ball of the rail. The other rear leg 13 is pivotally attached to the base 85 of the skid and has an aperture 14 through which extends a lug 15 formed on the shoe. This lug has an aperture through which a pin or bolt 16 may be passed to lock the leg 13 securely in place.

Attached to the skid or bumper is a flat 90 spring arm 36 which extends forwardly therefrom and carries a bracket 17 at its outer end. This bracket consists of two plates 18 and 19 between which are mounted small rollers. The rollers 20 are adapted to ride the track while the larger roller 21 will be engaged by the car wheel during the return movement, as best shown in Fig. 1.

Attached to the outer side of the rail at 100 the desired point ahead of the permanent stop, is a cam block 22 which is adapted to contact with the spring arm 36 and move the bracket and the rollers away from engagement with the wheel allowing the car 105 to pass by the cam. The skid will then stop and remain on the track in its original forward position ready to receive and stop another car. The position of the cam block and its distance ahead of the permanent stop 110

block will determine the rail space over which the skid will travel, and this may be adjusted according to circumstances.

Another form of returning means is shown in Fig. 4 in which a bracket 32 is attached to the arm carried by the skid. In this form the bracket 32 is provided with two side pieces 23 suitably connected together by a back 24 which has an aperture 34 near its upper edge. A notched pin 25 is mounted in the bracket and slides through this aperture and through an alined aperture in the forward face of the bracket. A lever arm 26 is pivotally mounted in the bracket and has its upper end 27 received in the notch 28 in the pin. Its lower end extends down below the rail surface and is adapted to engage with the cam face 29 of a cam block 30 attached to the rail. Movement of the lever arm along this cam surface releases the pin and allows the car to move off the shoe which stops in the original position. The pin is normally held in its outward engaging position by the action of a spring 31 and is adapted to engage the car wheel inside of the flange so that when the car moves back, after being stopped, the skid will be returned to its forward position.

It will of course be understood that the bracket 32 may be attached directly to the skid instead of to an arm, it being only necessary to place the bracket in such position that when the car wheel is engaged by the pin 25, the wheel will have returned far enough to be standing on the track so that the pin carries only the load of the shoe sliding along the rail.

The present device is light enough to be moved from place to place, yet is strong enough to withstand the hard usage it will necessarily receive. The means for returning the skid or shoe to its normal position is of great importance as the shoe, after it receives a car wheel, slides along the rail, but the friction between the two is so great that the car is almost at a standstill when the shoe strikes the stop block on the rail. The parts may be made much lighter than where the car is to be stopped instantly because the friction between the skid and the rail acts as a brake and the stop block will be spaced back from the normal position of the shoe such a distance that the car will be almost stopped before the shoe contacts the stop.

Other modes of applying the principle of our invention may be employed instead of the one explained, change being made as regards the mechanism herein disclosed, provided the means stated by any of the following claims or the equivalent of such stated means be employed.

We therefore particularly point out and distinctly claim as our invention:—

1. In a car stop, the combination of a stop

block attached to the rail, a shoe slidably mounted on said rail in advance of said block and adapted to engage the car wheel, and means mounted on said shoe and adapted to engage the car wheel to return said shoe to its original position upon return movement of the car.

2. In a car stop, the combination of a stop block attached to the rail, a shoe slidably mounted on said rail in advance of said block and adapted to engage the car wheel, means attached to said shoe and being adapted to engage with the car wheel upon its return to move said shoe toward its original position; and other means adapted to disengage said first-named means from said wheel at a predetermined point.

3. In a car stop, the combination of a stop block attached to the rail, a shoe slidably mounted on said rail in advance of said block and adapted to engage the car wheel, an arm attached to said shoe and adapted to engage with the car wheel to return said shoe toward its original position upon the return of said car, and means mounted on the rail for disengaging said arm from said wheel.

4. In a car stop, the combination of a stop block attached to the rail, a shoe slidably mounted on the rail ahead of said block, said shoe being adapted to receive a car wheel thereon, a resilient arm attached to said shoe and extending along the rail, means attached to said arm and adapted to allow a car wheel to pass by on to said shoe, said means being adapted to engage the wheel upon its return movement to move said shoe to its original position, and other means attached to the rail and adapted to be engaged by said arm to disengage said means from the wheel at a predetermined point.

5. In a car stop, the combination of a stop block attached to the rail, a shoe slidably mounted on the rail ahead of said block, said shoe being adapted to receive a car wheel thereon, a resilient arm attached to said shoe and extending along the rail, means attached to said arm and adapted to allow a car wheel to pass by on to said shoe, said means being adapted to engage the wheel upon its return movement to move said shoe to its original position, and a cam block attached to the rail and adapted to be contacted by said arm during its return movement to disengage said means from the wheel to stop said shoe at its forward position.

6. In a car stop, the combination of a stop block attached to the rail, a shoe slidably mounted on said rail ahead of said block, said shoe being adapted to receive a car wheel thereon, a resilient arm attached to said shoe and extending forwardly along the rail, a bracket attached to the outer end of said arm, wheel engaging means mounted in

said bracket and adapted to engage the car wheel to move said shoe to its original forward position upon return movement of the wheel, and cam means for disengaging 5 said wheel engaging means from said wheel upon return movement.

7. In a car stop, the combination of a stop block attached to the rail, a shoe slidably mounted on the rail ahead of said block, said shoe being adapted to receive a car wheel thereon, a resilient arm attached to said shoe and extending along the rail, a wheel mounted in said arm and adapted to ride on the rail, a second wheel mounted 10 above said first wheel and adapted to be engaged by the car wheel upon return movement to move said shoe back to its original position, and a cam block adapted to be attached to the rail and to be engaged by said arm during its return movement to disengage 15 said wheel from the car wheel and stop said shoe in its original position.
8. In a stop for railway cars and the like, the combination of a permanent stop block 20 adapted to be secured to the rail, and a portable shoe adapted to be slidably mounted on the rail, said shoe being adapted to receive a car wheel thereon and to move therewith until stopped by said block.
9. In a stop for railway cars and the like, 25

the combination of a permanent stop block adapted to be secured to the rail, and a slideable shoe adapted to be clamped to the rail and spaced ahead of said block, said shoe being adapted to receive a car wheel 30 thereon and move therewith until stopped by said block.

10. In a stop for railway cars and the like, the combination of a permanent stop block adapted to be secured to the rail, and 40 a slideable shoe adapted to be removably mounted on the rail and spaced ahead of said block, said shoe being adapted to receive a car wheel thereon and move forward therewith to stop the wheel and car when 45 in contact with said block.

11. In a stop for railway cars and the like, the combination of a permanent stop block adapted to be secured to the rail, a shoe adapted to be removably clamped on 50 the rail and slideable along, said shoe being spaced ahead of said block, said shoe being adapted to receive a car wheel thereon and move therewith to stop the car when in contact with said block. 55

Signed by us this 16th day of November, 1917.

EDWARD W. BREYLEY.
JAMES U. DUFFY.
